(57) **CLAIM**

The ornamental design for a crown bit, as shown and described.

DESCRIPTION

FIG. 1 is a perspective view of a crown bit according to the present design;

FIG. 2 is a perspective view of a crown bit according to an alternative embodiment of the present design;

FIG. 3 is a top plan view of the crown bits of FIGS. 1 and 2;

FIG. 4 is a bottom plan view of the crown bits of FIGS. 1 and 2;

FIG. 5 is a right side elevation view of the crown bits of FIGS. 1 and 2; and

FIG. 6 is a front side elevation view of the crown bits of FIGS. 1 and 2; and,

FIG. 7 is a perspective view of the crown bits of FIGS. 1 and 2 and a drill bit, wherein the broken lines illustrate components that form no part of the design.

The broken lines in the figures are for illustrative purposes only and form no part of the claimed design.
